FOOT TRACTION HITCH

John R. Siebrandt, Kansas City, Mo.; Elizabeth Siebrandt, executrix of said John R. Siebrandt, deceased, assignor, by mesne assignments, to Siebrandt, Inc., Kansas City, Mo., a corporation of Missouri

Application November 15, 1948, Serial No. 60,009

4 Claims. (Cl. 128—83)

This invention relates to improvements in a removable traction hitch for maintaining traction on the leg when reduction of a fracture thereof is to be made and while applying a cast.

The principal object of the present invention is the provision of removable traction hitch having hinged traction straps adapted to engage the foot before a plaster cast is applied thereto, and that can be easily and quickly removed from the finished cast without disturbing the alignment of the fractured parts.

Another object of the invention is the provision of a removable traction hitch having a U-shaped frame adapted to be drawn from the finished cast and to remove the traction straps therewith.

Other objects are simplicity and economy of construction, ease and efficiency of operation and adaptability for use in various orthopedic operations.

With these objects in view as well as other objects which will appear in the course of the specification, reference will be had to the drawing wherein:

Fig. 1 is a side elevational view of foot and leg portion having the removable traction hitch positioned thereon to create a traction while a plaster cast, shown in section, is being applied.

Fig. 2 is a plan view of the assemblage shown in Fig. 1 with the cast partly broken away to more clearly show the operating parts.

Fig. 3 is a side elevation of the foot and leg with the removable plaster hitch partially positioned thereon.

Fig. 4 is a fragmentary, enlarged section taken on line IV—IV of Fig. 1.

Fig. 5 is an enlarged perspective view of the frame portion of the hitch, with one of the strap retaining arms opened.

Fig. 6 is a layout view of one of the traction straps, with the assembling wire in place.

Fig. 7 is a sectional view taken on line VII—VII of Fig. 6.

Fig. 8 is a detached view of the toe guard.

Fig. 9 is an enlarged sectional view taken on line IX—IX of Fig. 4.

Throughout the several views like reference numerals refer to similar parts, and the numeral 10 designates a frame of general U-shape, preferably made of metal to present a relatively rigid structure having a base 12 and outwardly projecting, substantially parallel arms 14. The end portions of said arms are adapted to be positioned respectively at opposite sides of the foot 16 and substantially in alignment with the leg 18. Adjacent its free end each of arms 14 is

provided with a rigidly mounted, outwardly projecting pin 20, the pins carried by both of arms 14 being in axial alignment with each other. Arms 14 are adapted to lie substantially flat along the sides of foot 16, and have sufficient resilience to accommodate themselves readily to feet of different thickness.

A dorsal strap 22 and a heel strap 24 are adapted to be passed respectively over the dorsum and under the heel of the foot, and to be secured adjacent their ends to pins 20. Said straps are substantially similar, and as shown in Figs. 6 and 7, each strap comprises a pair of like sections 26 and 28. Each of said sections is made of a length of fabric or other pliable material folded along its midline and with the halves thereof cemented or otherwise joined together. Along its folded edge, each section is cut out to present a series of spaced apart loops 30 adapted to be placed in alternating relation with the loops of the other sections, and the sections joined together by inserting a soft metal wire through said loops. The sections of the dorsal strap are joined by wire 32 which extends along the upper side of the foot to a point spaced outwardly from the toes, and the sections of the heel strap are joined by wire 34 which extends below the heel. Adjacent each of its ends, each strap is provided with an eyelet 36, said eyelets being adapted to pass freely over pins 20.

Said eyelets are retained on pins 20 by means of a retaining arm 38 pivotally secured to each of frame arms 14 at a point spaced apart from pin 20 by suitable means such as rivet 40. The free end portion 42 of arm 38 is offset outwardly to be normally in parallel, spaced relation to arm 14, and is provided adjacent its end with a transverse notch 44 adapted to fit over pin 20 adjacent the outer end thereof. Traction straps 22 and 24 engage pin 20 between arms 14 and 38, and are attached thereto when arm 38 is pivoted upwardly as shown in Fig. 3. An upset boss 46 formed on arm 38 is adapted to engage resiliently a recess 48 formed therefor in the adjacent portion of arm 14, thereby normally holding arm 38 in engagement with pin 20. Along its upper edge, the offset portion 42 of each arm 38 is provided with an inwardly projecting flange 50 which normally contacts arm 14 and prevents the entry of plaster between the two arms.

The parts then have the relative positions shown in Fig. 3. Normally both the foot and the traction straps are coated with petroleum jelly or oil to prevent adhesion of the plaster cast. A

cord 52 is attached to base 12 of frame 10 by means of S-hook 54, and extends to a suitable means, not shown, for applying traction to leg 18 through frame 10 and traction straps 22-24. Normally the leg is carried on a suitable support, not shown, as traction is applied and a fracture reduced. A toe guard 56 adapted to prevent formation of the cast solidly around the toes is placed in position. Said guard comprises a piece of sheet metal of substantially V-shape adapted to fit over the toes and provided at its folded edge with a hole 58 through which wire 32 passes. A plaster cast 60 may then be applied to the leg and foot in the usual manner. It will be noted in Fig. 4 that the offset portions 42 of arms 38 are sufficiently long to project outside of the cast. Thus each arm 14 and the associated arm 38 forms a window 62 into the cast.

While the cast is still moist, the plaster may be trimmed about the toes and the toe guard 56 removed, and the plaster cut away to provide tapering entries to windows 62. When the cast has set sufficiently to permit the traction to be removed, the traction is first reduced by slackening cord 52, and wires 32 and 34 are then drawn longitudinally outwardly through the mold. Said wires are sufficiently pliable that this may be done easily. Frame 10 may then be drawn out of the cast and the straps 22 and 24 will be drawn through windows 62, each arm 14 of the frame carrying one section of the dorsal strap 22 and one section of the heel strap 24. Each window 62 is of ample area to permit the passage of the straps. It will be noted that since each strap section is seamless and of uniform thickness, it may be drawn easily from the cast. Seams would cause localized bulk in the straps which might present obstructions to easy passage through the cast.

Thus it will be seen that no part of the hitch remains inside of the cast to cause possible pressure on the foot or leg. If desired, windows 62 may be filled with additional plaster after the hitch has been removed. The hitch may be reassembled for further use by inserting wires 32 and 34 through loops 26 of the straps. And although the hitch has been shown for use in connection with treatment of fractures of the leg, it is readily apparent that it could be adapted for use in various other orthopedic operations without departing from the spirit of the invention.

What I claim is:

1. A traction hitch for applying traction to a fractured leg as a cast is applied thereto comprising a frame member having substantially parallel arms adapted to extend closely adjacent the sides of the foot and substantially in alignment with the leg, a strap retaining arm secured to each of said frame arms and having a portion disposed in parallel, spaced relation from the end portion of said frame arm, a pair of pliable traction straps each comprising a pair of separable sections adapted to pass respectively over the dorsum and behind the heel and secured at their ends between said frame arms and the associated retainer arms, members releasably connecting the sections of said straps, whereby traction may be applied to said leg through said frame and whereby a plaster cast may be formed about said foot and leg over said straps and with said frame arms extending outwardly from said cast, said connecting members being operable

from outside of said cast to separate said strap sections whereby said frame may be withdrawn from said cast, each of said frame arms and its associated retainer arm providing a window in said cast through which said straps are drawn.

2. A traction hitch for applying traction to a fractured leg as a cast is applied thereto comprising a frame member having substantially parallel arms adapted to extend closely adjacent the sides of the foot and substantially in alignment with the leg, an outwardly projecting pin carried rigidly adjacent the end of each of said arms, a pair of pliable traction straps each divided intermediate its ends, a member releasably connecting the sections of each of said straps, said straps being adapted to pass respectively over the dorsum and behind the heel and having eyelets adjacent their ends adapted to be passed over said pins, a strap retainer arm carried pivotally by each of said frame arms and having a portion normally disposed in spaced relation from said frame arm and engaging said pin adjacent its outer end to retain said straps thereon, whereby as a plaster cast is formed about said leg and foot said frame arms and retainer arms will project outwardly from said cast, said connecting members being removable from outside said cast for dividing said straps, whereby said frame and said straps may be drawn from said cast.

3. In a traction hitch of the class described for applying traction to a fractured body member as a plaster cast is formed thereabout and including a frame member adapted to extend into said cast, a pliable traction strap adapted to pass about said body member and joined adjacent its ends to said frame, said strap being divided transversely intermediate its ends into two sections, the adjacent edges of said sections being formed to present loops, and a wire passing through said loops to connect said strap sections, said wire being adapted to extend outwardly through said cast.

4. The combination, with a traction hitch of the class described for applying traction to a fractured leg as a cast is formed thereabout and including a frame having a pair of substantially parallel arms adapted to extend into said cast substantially in alignment with the leg and an outwardly extending pin carried rigidly adjacent the inner end of each of said arms, of a pair of traction straps adapted to pass respectively over the dorsum and behind the heel of the foot, each of said straps comprising two sections, each of said sections comprising a length of pliable material doubled on itself, said sections having their doubled edges adjacent and forming loops, a wire passing through said loops to join said sections and passing outwardly through said cast, and eyelets inserted adjacent the ends of said straps and adapted to be carried pivotally on said pins.
